UNITED STATES PATENT OFFICE.

ROBERT D. BAKER, OF BIRMINGHAM, MICHIGAN.

FINE-GRADING MACHINE FOR HIGHWAY CONSTRUCTION.

Application filed December 3, 1924. Serial No. 753,560.

This invention relates to subgrading machines particularly adapted for preparing the foundation or subsurface of paved streets, roads and the like, and has for its 5 object to provide a simple and efficient machine or device of this character.

In the construction of concrete and other highways, the modern practice is to first rough-grade the subsurface to within about 10 two inches above the ultimate or fine-grade upon which the pavement is to be laid. The rough-grading is accomplished by means of plows and road-scraping machines. Stakes are then driven at intervals in proper position relative to the side edges of the ultimate pavement for the support of the chalk lines affording the guiding means determining pavement crown and width.

Following the staking and drawing of 20 these guide lines, the trenching for the side-rails or forms is effected, this being ordinarily followed by laying the said side-rails, the latter being, in some instances, employed to support a fine-grading machine or device 25 and thereafter to support a surfacing machine, there being several of the latter in very general use.

The most commonly used paving material of the present day is concrete and the 30 most universal type of concrete pavement laid outside of city streets is that which is known as a single course pavement, as distinguished from the two-course type consisting of a sublayer and a finishing layer 35 of paving materials.

Following rough-grading and laying of side-rails, and frequently, following fine grading, the concrete mixer of the boom and bucket caterpillar tractor type, is run 40 onto the sub-surface, either rough or fine, and moves in advance of the pavement as the latter is laid between the side forms. Where the mixer is run on the rough grade, 45 the fine grading is usually effected manually by shovels between the mixer and the point of last deposit of the concrete. This is, in fact, the most common procedure because of the fact that the mixer is supplied 50 with its charges of ingredients by means of trucks traveling upon the subgrade from the stock-sheds and heaps some distance beyond the point of operation of the mixer.

These trucks produce ruts and mitigate against fine-grading except between the mixer and point of deposit of batches. 55

In many instances, however, the hauling of ingredients is effected over a narrow gauge railway disposed at one side of the roadway beyond the stake-line or laid in the middle of the roadway. This means of 60 transportation obviates rutting and permits fine-grading far ahead of the point of immediate operation, the expense of this railway equipment being such that comparatively few road-building contractors 65 have it.

In some instances planks are laid upon advance fine-grades for supply motor-trucks to run upon to prevent rutting.

My present invention has for its object to 70 provide a fine-grading machine which may be embodied as a motor-actuated or as a manually operable machine for effecting long stretches of fine-grading in advance of pavement laying where the mode of supplying the concrete mixer is such as to obviate rutting and cutting up of the fine grade. 75

A further object of the invention, applying with equal force to the several types 80 above indicated, is to provide a fine-grading machine wherein the earth cutting element is slightly reciprocated during travel of the carriage and wherein the cutting element is bodily adjustably relatively to the carriage 85 to permit the fine-grading to be accomplished by a single passage or by several passages of the machine over the rough-grade, the several passages removing surplus earth by courses or layers and being necessary under 90 some conditions. A further object of such adjustment is to permit the carriage to travel upon the high side rails of the form and to also permit temporary use of far lower rail road rails temporarily laid in the trenching 95 for the side-rails where fine grading proceeds far in advance of mixer operations.

Other objects of the invention will appear in or from the following specification.

Subgrading machines embodying the invention are fully illustrated in the accompanying drawings, wherein:

Fig. 1 is a top plan view of a motor propelled and motor actuated subgrading ma-

chine constructed in accordance with my invention.

Fig. 2 is a front elevation of the same.

Fig. 3 is a vertical longitudinal section of 5 the same on the line 3—3 of Fig. 1.

Fig. 4 is a fragmentary vertical transverse section of the same on the line 4—4 of Fig. 1.

Fig. 5 is a detail section of the same on the line 5—5 of Fig. 3.

10 Fig. 6 is a top plan view of a manually operable subgrader constructed in accordance with the invention.

Fig. 7 is a front elevation of the same.

15 Figs. 8 and 9 are vertical longitudinal sections on the line 8—8 of Fig. 6 showing the relatively movable parts thereof in respectively different positions.

Fig. 10 is a fragmentary detail section on the line 10—10 of Fig. 8.

20 Fig. 11 is a diagrammatic view illustrative of the nature of the fine-grade surface produced by the machines illustrated.

The machine comprises a suitable carriage which may be conveniently constructed from 25 commerical structural steel units of types and sizes adapted to the purpose. The said carriage comprises the side-frames or trucks 1 each equipped with a pair of flanged wheels 2 adapted to run on rails 3 which may be of the standard type of railroad-rail or 30 of the type which is commonly used to constitute the side walls of the form for receiving the plastic concrete of the pavement structure. The wheels 2 are preferably 35 flanged along both edges and present intermediate faces of considerably greater width than the crowns of the rails 3 so as to avoid the necessity of too accurately spacing the latter. The rails are laid upon the flat bottom 40 of the trenches at each side of the roadway which are dug after rough-grading has been completed, said trenches being at least as wide as the blade of the shovel used by the person digging the same and thus permitting 45 some lateral displacement or adjustment of rails laid thereon. Where the railroad-rails are employed, their use is temporary and precedes the more accurate laying of the side-rails of the pavement form (which are 50 also known as "side-forms") and the wide faces of the wheels obviate the accurate laying of said temporary rails to accommodate the carriage.

The said side-frames 1 are connected in 55 fixed parallel relation by means of a plurality of cross-beams 4, 5, 6, 7 and 8, said members 4 and 7 being connected to the ends of the side-frames or trucks between the upper and lower faces of the latter the element 6 being disposed between and on the same level as said elements 4 and 7, while the elements 5 and 6 are secured to the lower faces of the side-frames or trucks between the ends thereof. Further bracing elements 60 65 may be employed as desired, it being under-

stood that the details of construction of the frame may be changed and varied as engineering skill and practice dictate, it being particularly desirable to render said frame as light as possible with relation to 70 the degree of inflexibility requisite to proper operation of the mechanism supported thereby to insure proper performance of function by said mechanism.

A further structural steel unit, such as a 75 heavy angle-iron 10 extends parallel with and contiguous to the element 5 of the frame and is secured at its ends to the side frames of trucks 1. On the lower face of the angle-bar 10 there are mounted the bearings for a shaft 10^a equipped with a plurality of eccentrics 10^b which are operatively associated with the shovel element 11 which consists of a steel plate substantially the same length as the said angle bar 10 and which is of such width that, normally, its inclination from its upper to its front or cutting edge will approximate an angle of about thirty to forty degrees to the horizontal plant of said hinged edge. The front or cutting edge of said blade or shovel-member 11 is preferably slightly serrated and is also bent or formed to correspond to the lateral contour of the fine-grade of the pavement foundation if the latter be other than perfectly plane. The said shovel element may be constructed of several parts, including suitable stiffening or reinforcing means such as the angle-bar 12 without departing from the invention, the latter being herein illustrated in a 100 simple and more or less diagrammatic manner.

Between the upper and cutting edges of said shovel element 11, the latter is provided with a plurality of, preferably, rectangular openings 13 each of which is adapted to be closed by a suitable gate 14, said openings being suitably spaced from each other. All of the gates 14 are rigidly mounted on a rock-shaft 15 journalled in bearings on the nether face of the shovel element 11, for simultaneous operation of said gates 14, said shaft being equipped with a lever 17 at one end for rocking the same. A notched quadrant 18 disposed on the shovel 11 in engaging relation to the spring-held dog 19, operable by means of the grip-lever 20 on said lever 17, serves to maintain the several series of gates 14 in either open or closed position.

Connected with the cutting edge-portion of said shovel 11, by means of universal joints 21, is a plurality of screw-shafts 22 each equipped with a hand-wheel 23 or the like. Said screw-shafts 22 engage in threaded sleeves 25 pivotally associated with yokes 26, the latter being pivotally associated with the frame element 6 and also, coincidentally with the pivotal connections thereof with said sleeves 25, said yokes are 115 120 125 130

5 pivotally associated with the lower ends of the forked connecting rods 27 reciprocable by means of eccentrics on the shaft 28 extending parallel with and journaled in bearings carried by said frame element 6.

10 The shaft 28 is suitably operatively geared to the shaft 29 of the motor 30 which is conveniently mounted on one of the side frames 1, a clutch operable by the lever 31 15 being suitably interposed in said gearing for controlling the operation of said shaft 28.

15 Said shaft 28 is geared to the shaft 10^a by means of sprockets 28^a and sprocket-chain 28^b for rotation of said shafts 10^a and 20 28 in unison at, preferably equal speeds to thereby impart to the shovel element 11 a compound motion whereby its cutting edge is reciprocated back and forth at the same time as it is raised and lowered, the eccentrics on said shafts being relatively disposed to synchronize the respective movements in any desired relation to each other.

25 Depending from the carriage is the framing 32 supporting the bearings of the shafts or trunnions of the pulleys 33 over which a conveyor-belt 34 is trained, one of said pulleys 33 being operatively geared to the motor-shaft 29, the clutch operable by the lever 35 being interposed in the connection. 30 This belt 33 is disposed mainly below the shovel 11 and is adapted to receive earth passing through the openings 13 in said shovel when the gates 14 are open. The said belt extends substantially from one 35 side-frame or truck 1 to the other and travels in a direction to deliver earth carried thereby to the conveyor-belt 36 trained over pulleys 37 suitably rotatably mounted in the projecting frame-portion 38 of the carriage, said gearing being conveniently exemplified by the worm 39 and worm-wheel 40. The latter is appropriately operatively associated also with wheels 2. A clutch 45 operable by the lever 41 controls the travel of the carriage in the forward direction, there being no reversing-gear illustrated or necessary inasmuch as reverse travel of the carriage is easily accomplished manually by the operators in attendance.

50 The shovel 11 is illustrated in Fig. 3 as disposed at its maximum elevation in the course of operations. It may be lowered to effect deeper cut by manual operation of the screw-shafts 22 which are reciprocated in unison with the slight motions of the shovel as imparted thereto by the eccentrics on the shafts 28 and 10^a. As the carriage travels forward, these slight motions of the shovel serve to break up the earth at the same time that it is cut into and also assist in causing the loosened earth to move up the shovel and upon the angle-bar 10. When the gates 14 are open, a large part of the earth will pass through the same, it being very desirable 55 that some thereof be available to operators

in attendance to be shoveled back upon the fine-grade behind the machine to fill any hollows occurring therein, all earth accumulating on the shovel in excess of requirements for filling hollows, being manually moved to 70 drop through the openings 13 or being shoveled to the opposite side of the roadway from that to which the conveyor-belts deliver the earth for filling voids at the said other side. The reciprocatory movement of 75 the shovel also assists greatly in the removal of pebbles of considerable size sometimes encountered and to cause the shovel to pass over those of too large size to be liberated by the shovel. The latter possesses sufficient 80 resiliency to resist permanent distortion due to collision with or riding over obstructions which it is incapable of dislodging. Such collision would cause the carriage to cease 85 traveling while during the interval of riding over an obstruction the carriage would be lifted at least in part and be, to that extent, carried by the portion of the shovel resting on the obstruction. The operator 90 would, obviously, quickly throw the levers 41 and 31, then manually reverse the travel of the carriage and remove the obstruction.

95 The structure of Figs. 1 to 5 inclusive is particularly intended and adapted for fine-grading the earth foundation of the pavement where such work is practicable far in advance of the point of operation of the mixer, while that shown in Figs. 6 to 10 inclusive is better adapted for piecemeal fine-grading as above pointed out, and for long 100 stretches of advance work when drawn by a suitable tractor or other means, its use in both kinds of work above noted, being, it is believed, far more economical than and superior to that performed by hand labor 105 and by any other machines now in general use.

110 The structure of Figs. 6 to 10 includes the side-frames or trucks 42, wheels 43 and connecting frame elements 44, 45, 46 and 47 and some suitable bracing members 48, the angle-bar 49; the shovel 50 hinged to the angle-bar 49, the screw-shafts 51 having threaded engagement between their ends with the sleeves 52 pivotally mounted on the frame-element 47, and the universal joint connections 53 of the screw-shafts with the cutting edge portion of the shovel, the number and relative positions of the frame elements 44 to 47 inclusive being slightly different 115 from the similar parts of the structure of Figs. 1 to 5 inclusive.

120 The side frames 42 are split between their ends as shown at 54 to divide each thereof into two parts, one thereof indicated by reference character 42 and the other by reference character 55, which are secured together by means of the hinges 56 mounted on their lower faces, the opposed ends of the separable parts normally abutting against 125 130

each other by gravity. The smaller end portion 55 of each side frame is provided with an upwardly extending flange 57, while the portion 42 carries a foot lever 58 of the bell-
 5 crank type having a very long main portion and a very short angular end portion, the latter equipped with the anti-friction roller 59. Said levers 58 are rigidly mounted at their elbows at opposite ends of the shaft 60
 10 journaled in bearings 61 carried by the frame element 46 which is supported upon the upper faces of the portions 42 of the side-frames in such position that the rollers 59 normally bear against the flanges 57. Each
 15 member 42 of the side-frames is equipped with a railing 62 disposed inwardly thereof so as to permit an operator to stand on said side-frame portion 42 and hold on to said railing while with one foot he successively
 20 depresses and raises the long end portion of the lever 58 as the carriage moves forward. This relative pivotal movement of the two parts of the side frames as is illustrated by Figs. 8 and 9 and a substantially vertical
 25 reciprocatory movement of the cutting edge of the shovel. The earth piling up on the latter is shoveled to the sides of the roadway and into hollows and voids occurring in the fine grade by operators conveniently standing on the angle-bar 49.

It will be obvious that the cut made by the shovel must of necessity produce a fine-grade which presents a minutely corrugated surface. In practice the cutting edge of the
 35 shovel is set so that in its lower position its lower edge lies in the predetermined grade-plane and in its higher position it is disposed above the same. The stroke of this edge will range from a minimum of about
 40 one-quarter of an inch to a maximum of possibly three quarters of an inch, depending upon the nature of the earth.

In the operation of the power actuated machine the reciprocatory movements of the
 45 cutting edge of the shovel are so regulated as to the number of said reciprocatory movements per foot of travel of the carriage that the fine-grade surface produced presents a very smooth appearance to the naked eye,
 50 that is to say, to present a surface which reveals lateral ridges and depressions only upon very close inspection. As above pointed out, the reciprocatory stroke of the shovel is very limited and, generally, of a maximum far below the depth of the soil layer
 55 to be removed from above the fine-grade plane, the action of the cutting edge of the shovel being, under the influence of the compound movement above described, to substantially pulverize or break up into small
 60 fragments a thin layer of compacted earth disposed directly above the fine-grade plane and between the latter and the surface of the rough-grade, the surface earth to be re-
 65 moved being thus undermined and broken

up into relatively small lumps. The rough-grade is first undermined by the shovel edge and thereafter, by further penetration of the latter and due to either the inclination of the upper surface of the shovel
 70 or to the slight up and down strokes of the latter, the earthcrust above the zone of undermining by the cutting edge, is raised and broken up and caused to mount or ride over the top rear edge of the shovel as the latter moves forward. Following passage of the machine, the surface is subjected to the action of a heavy roller which eliminates the corrugations and provides a perfectly
 75 smooth fine-grade.

In so far as undermining the layer of earth to be removed consists in effecting a pulverization or breaking up, as aforesaid, of a thin layer thereof immediately overlying the fine-grade plane, is concerned, the invention includes a seemingly entirely novel method as distinguished from past practices so far as the same are known to me.

In the case of the manually operable machine of Figs. 6 to 10, inclusive, as well as in the case of the power actuated machine, when only the up and down movement of the shovel edge is effected as in the manually operated device, the cutting edge of the shovel is set so that in its lowest position
 90 it is disposed slightly below the exact fine-grade plane and, in fact, so that the latter lies midway between the limits of up and down reciprocatory or rocking movements of the cutting edge of the shovel thereby producing a slightly corrugate surface, the ridges and hollows of which are disposed substantially equal distances above and below the actual fine-grade plane. The mean length of the corrugations depends upon the number of reciprocatory strokes of the shovel edge per foot of travel of the carriage. In actual practice the speed of reciprocation of the shovel edge is about six up and six down strokes per foot of travel of the machine and the length of said stroke is approximately one-half inch, these movements of the shovel edge being variable without departing from the invention.

A simple lateral movement of the cutting edge of the shovel relative to the ultimate fine-grade plane does not effect a pulverization or breaking up into substantially such state the thin layer of compact earth disposed in the path of the cutting edge but does effect the breaking up into small lumps of the earthcrust or masses to be removed and this is all that is necessary to effect removal by the belt conveyor associated with the power machine and facilitates manual removal in the case of the manually operable machine.

Expressed in terms of method the invention consists broadly in maintaining the shovel edge at all times below the surface

of the earth crust to be removed, causing the shovel to travel continuously in one general direction while so maintained, and imparting to it during such travel a slight 5 movement laterally of the general direction thereof.

It will be obvious, of course, that the accuracy of the fine-grade is dependent upon the accuracy with which the side rails of 10 the form are laid and this, in turn, is dependent upon the accuracy of the trenching for the side rails. The machines as illustrated are intended for riding on side rails but may be designed for travel in the side 15 rail trenches or their equivalent in instances where side rails are not employed. In many instances the side rails may be the crowns or gutters of curbing.

In practice the up and down movements of 20 the shovel edge causes the latter to dislodge rocks and pebbles of considerable size embedded or partially embedded in the road-bed without undue strain or stress on the machine or shovel edge, this being exceedingly 25 advantageous.

Practice has demonstrated that the conventional road scraper wherein the scraper blades are rigid with respect to the carriage, will remove or cut away only a very thin 30 layer of compact earth in a single passage over the area to be fine-graded. Rough grading by means of plows leaves from one to six inches depth of compact earth crust to remain over the ultimate fine-grade plane, 35 and in most instances all of this surplusage is removed by a single passage of the machine of this invention over said area. This is possible only by effecting the lateral movement of the shovel edge during forward 40 travel.

In Fig. 11 I have illustrated the grade-plane in dotted lines and the corrugations produced by the cutting edge of the shovel in full lines. From this figure it will be seen 45 that the hollows of the corrugated surface are as far below the dotted line as the ridges are above the same, the depth of the hollows measured from the tops of the ridges being equal to the stroke of reciprocation of the 50 shovel-edge, said stroke being adjustable by connecting the rods 16 in various openings in the links 26 as shown in Figs. 3, 4 and 5 and the wave length of the corrugations being dependent upon the ratio of forward 55 travel of the carriage in feet per minute to the number of reciprocatory strokes per minute. In practice the grade surface appears substantially smooth to the eye, the undulations being seen only on close inspection. 60

While I have confined the illustrations and description to means for imparting substantially vertical reciprocatory movements to the shovel edge, the invention comprehends the broad idea of simultaneous move-

ments in divers directions within the definition of the appended claims.

I claim as my invention:

1. A fine-grading machine including a wheeled frame adapted to be supported on 70 rails disposed over opposite sides of the area to be fine-graded, a shovel carried by said frame disposed at an incline to the plane of the ultimate fine grade with its cutting edge substantially in said plane, and means for 75 imparting a slight reciprocatory movement to the cutting edge portion of said shovel successively during travel of said carriage forwardly along said rails to provide for successive elongated surface removing cuts transverse of an uneven road surface to grade it uniformly throughout. 80

2. A fine-grading machine including a wheeled frame adapted to be supported on 85 rails disposed upon opposite sides of the area to be fine-graded, a shovel carried by said frame disposed at an incline to the plane of the ultimate fine grade with its cutting edge substantially in said plane, and means for 90 imparting a slight reciprocatory movement to the cutting edge portion of said shovel successively during travel of said carriage along said rails to provide for successive elongated surface removing cuts transverse of an uneven road surface to grade it uniformly throughout, and means for adjusting vertically the cutting edge portion of the 95 shovel relative to the plane of support of the carriage. 100

3. A fine-grading machine including a wheeled frame adapted to be supported on 105 rails disposed upon opposite sides of the area to be fine-graded, a shovel carried by said frame disposed at an incline to the plane of the ultimate fine grade with its cutting edge substantially in said plane, and means for 110 imparting a slight reciprocatory movement to the cutting edge portion of said shovel successively during travel of said carriage in the direction of projection of the said cutting edge portion of said shovel to provide for successive elongated surface removing cuts transverse of an uneven road surface to grade it uniformly throughout and means for 115 adjusting the cutting edge portion of the shovel relative to the plane of support of the carriage the said adjusting means being wholly independent of the means for imparting reciprocatory movement to said shovel. 120

4. A fine-grading machine including a 125 wheeled carriage adapted to travel on rails disposed upon opposite sides of the area to be fine-graded, a shovel carried by said frame and extending substantially the entire width of said area and having its cutting-edge disposed substantially in the plane of the said ultimate fine-grade, means for adjusting the elevation of said cutting edge of said shovel relative to the plane of support of the 130 wheeled carriage, a motor on the latter, man-

ually controlled gearing between said motor and the carriage, and manually controlled gearing between the motor and the shovel for imparting to the latter a slight reciprocatory movement.

5. A fine-grading machine including a wheeled carriage adapted to travel on rails disposed upon opposite sides of the area to be fine-graded, a shovel carried by said frame 10 and extending substantially the entire width of said area and having its cutting-edge disposed substantially in the plane of the ultimate fine-grade, means for adjusting the elevation of said cutting edge of said shovel 15 relative to the plane of support of the wheeled carriage, a motor on the latter, manually controlled gearing between said motor and the carriage wheels for propelling the carriage, and manually controlled gearing 20 between the motor and the shovel for imparting to the latter a slight reciprocatory movement, said shovel disposed at an incline for causing earth displaced thereby to move toward its upper edge, there being 25 openings in said shovel through which a part of the said earth may pass, conveying means disposed to receive the earth passing through said openings and deliver the same beyond the rail at one side of said area, and 30 manually controlled gearing between said conveying means and said motor.

6. A fine-grading machine including a wheeled carriage adapted to travel on rails disposed upon opposite sides of the area to 35 be fine-graded, an inclined shovel hinged to said frame and extending substantially the entire width of said area and having its cutting edge disposed substantially in the plane of the ultimate fine-grade, conveying 40 means associated with said shovel, means for imparting a slight reciprocatory movement to said shovel during travel of said carriage, a motor on the latter, and manually controlled gearing between said motor, the carriage wheels, the conveying means and the 45 said shovel for operating the same independently or in unison.

7. A fine-grading machine including a wheeled carriage adapted to travel on rails 50 disposed upon opposite sides of the area to be fine-graded, a downwardly inclined shovel hinged at its top to said frame and extending substantially the entire width of said area and having its cutting-edge disposed substantially in the plane of the ultimate 55 fine-grade, means for adjusting the elevation of said cutting edge of said shovel relative to the plane of support of the wheeled carriage, conveying means associated with said shovel, mechanism operatively associated with said shovel for imparting a slight reciprocatory movement thereto during travel of said carriage, a motor on the latter, and manually controlled gearing between 60 said motor, the carriage wheels, the convey- 65

ing means and the said mechanism for operating the same independently or in unison.

8. A fine-grading machine including a wheeled carriage adapted to travel on rails disposed upon opposite sides of the area to 70 be fine-graded, a shovel carried by said frame and extending substantially the entire width of said area and having its cutting-edge disposed substantially in the plane of the ultimate fine-grade, said shovel disposed at an incline adapted to cause earth displaced thereby to move over its surface, there being a plurality of openings in the shovel through which a part of said earth is adapted to pass, manually operable gates for 75 closing said openings, conveying means disposed to receive the earth passing through said openings and carry the same beyond one of the said rails, mechanism for imparting reciprocatory motion to the shovel 80 during travel of the carriage, a motor on the latter, and manually controlled gearing between said motor, the carriage wheels, the conveying means and the said mechanism for operating the same independently or in 85 unison.

9. In a fine-grading machine, a carriage, an inclined pivotally supported shovel element, a motor with said carriage, and means associating said motor and shovel element 95 for imparting to the latter a compound motion including a forward and a substantially vertical reciprocatory movement.

10. In a fine-grading machine, a carriage, a motor and an inclined, pivotally supported 100 shovel element operatively associated with said carriage and motor, and means included in said association for imparting to said shovel simultaneously a forward and back reciprocatory movement and an up and down 105 rocking movement.

11. In a fine-grading machine, a carriage, a motor and an inclined, pivotally supported 110 shovel element operatively associated with said carriage and motor, and means included in said association for imparting to said shovel simultaneously a forward and back reciprocatory movement and an up and down rocking movement and means for adjusting 115 the extent of one of said movements.

12. In a machine of the kind specified, a carriage, a permanently inclined, pivotally supported shovel element mounted thereon, and means for simultaneously imparting to 120 said shovel, relative to said carriage, a reciprocatory movement longitudinally thereof and in substantially the directions of forward and reverse travel of said carriage, and a substantially vertical reciprocatory movement.

13. A fine-grading machine including a wheeled carriage adapted for travel on surfaces disposed upon opposite sides of the area to be fine-graded and extending parallel with the plane of the ultimate fine-grade of 130

- said area, a shovel blade operatively associated with said frame for rocking movement relative to the latter, a motor carried by and operatively associated with said frame 5 for propelling the latter and operatively associated with the shovel blade for rocking the latter to thereby impart to the cutting edge of the shovel blade a limited movement lateral to the ultimate fine-grade plane, 10 manually operable means controlling the association of the motor with said shovel blade, and manually operable means controlling the propulsion of the carriage by said motor.
- 15 14. In a fine-grading machine, a carriage adapted for travel in a predetermined plane parallel with the plane of the ultimate fine-grade, a motor on said carriage for effecting travel thereof, a shovel element on said carriage adjustable relatively thereto to dispose its cutting edge at any desired elevation relative to the plane of travel of the carriage, gearing between the motor and the shovel element to reciprocate the cutting edge of the 20 latter in a general direction lateral to the direction of travel of said carriage and shovel element during travel of said carriage.
- 25 15. In a fine-grading machine, a carriage adapted for travel in a predetermined plane parallel with the plane of the ultimate fine-grade, a motor on said carriage for effecting travel thereof, a shovel element on said carriage adjustable relatively thereto to dispose its cutting edge in a plane substantially coincident with that of the ultimate fine-grade, gearing between the motor and the shovel element to reciprocate the cutting edge of the latter in a general direction lateral to the direction of travel of said carriage and shovel element and with a stroke equal to a 30 fraction of the rate of travel of said carriage per minute during such travel.
- 35 16. In a fine-grading machine, a carriage adapted for travel in a predetermined plane parallel with the plane of the ultimate fine-grade, a motor on said carriage for effecting travel thereof, a shovel element on said carriage adjustable relatively thereto to dispose its cutting edge at any desired elevation relative to the plane of travel of the carriage, gearing between the motor and the shovel element to reciprocate the cutting edge of the latter during travel of the carriage substantially vertical of the ultimate fine-grade with a movement equal to a fraction of the depth of the earth to be removed.
- 40 17. In a fine-grading machine, a carriage adapted for travel in a predetermined plane parallel with the plane of the ultimate fine-grade, a motor on said carriage for effecting travel thereof, a shovel element on said carriage adjustable relatively thereto to dispose its cutting edge at any desired elevation relative to the plane of travel of the carriage,
- 45 18. In a fine-grading machine, a carriage adapted for travel in a predetermined plane parallel with the plane of the ultimate fine-grade, a motor on said carriage for effecting travel thereof, a shovel element on said carriage adjustable relatively thereto to dispose its cutting edge at any desired elevation relative to the plane of travel of the carriage, 50 gearing between the motor and the shovel element to reciprocate the cutting edge of the latter simultaneously in two directions during travel of the carriage, one of said movements being longitudinal to the direction of travel of the carriage and the other thereof lateral of said direction of travel.
- 55 19. In a fine-grading machine, a carriage adapted for travel in a predetermined plane parallel with the plane of the ultimate fine-grade, a motor on said carriage for effecting travel thereof, a shovel element on said carriage adjustable relatively thereto to dispose its cutting edge at any desired elevation relative to the plane of travel of the carriage, 60 gearing between the motor and the shovel element to reciprocate the cutting edge of the latter simultaneously in a plurality of directions with strokes of a degree constituting a fraction of the average depth of the earth crust mass to be removed.
- 65 20. In a fine-grading machine, a carriage adapted for travel in a predetermined plane parallel with that of the ultimate fine-grade, a motor on said carriage for effecting travel thereof, means on said carriage for effecting a breaking up into small fragments a thin layer of compact earth immediately above the plane of the ultimate fine-grade to thereby undermine and break up earth masses disposed above said layer, and gearing between the motor and said means for actuating the latter relative to said carriage simultaneously with travel of the latter.
- 70 21. In a fine-grading machine, a carriage adapted for travel in a plane parallel with that of the ultimate fine-grade, a motor on said carriage for effecting travel thereof, earth cutting means on said carriage adjustable in elevation relative to the plane of travel of the latter for effecting breaking into small fragments a thin layer of compact earth immediately above the ultimate fine-grade, gearing between said cutting means and said motor for actuating the former simultaneously with travel of the carriage and relative to the latter, earth conveying means on said carriage for removing the loosened earth, and gearing between said conveying means and said motor.
- 75 22. In a fine-grading machine, a carriage adapted for travel in a plane parallel with

- that of the ultimate fine-grade, a downwardly inclined shovel blade supported by and adjustable relatively to the carriage to dispose its cutting edge at any desired elevation relative to the plane of travel of said carriage, a motor on said carriage for effecting travel thereof, gearing between said motor and said shovel for imparting to the cutting edge of the latter a limited movement in part at least lateral to the plane of travel of the carriage during travel of the latter, earth removing mechanism disposed to receive loosened earth, and gearing between said mechanism and said shovel blade.
23. In a fine-grading machine, a carriage adapted for travel in a plane parallel with that of the ultimate fine-grade, a downwardly inclined shovel blade supported by and adjustable relatively to the carriage to dispose its cutting edge at any desired elevation relative to the plane of travel of said carriage, a motor on said carriage for effecting travel thereof, gearing between said motor and said shovel blade for imparting to the cutting edge of the latter limited movement in part at least lateral to the plane of travel of the carriage during travel of the latter, to thereby effect the breaking up of earth overlying the plane of the ultimate fine-grade, the said broken earth adapted to ascend the shovel blade, earth removing mechanism disposed to receive said earth as it passes over the rear edge of the shovel blade, gearing between said mechanism and said shovel, and gate controlled openings between the ends of said shovel for permitting deposit of loose earth upon the fine-grade rearward of the cutting edge of said shovel blade.
24. The method of fine-grading a pavement area which consists in maintaining earth cutting means in substantially the plane of the ultimate fine-grade, effecting continuous travel of said means, while thus maintained, in a general direction longitudinally of said area, and imparting thereto during said travel, a secondary movement lateral to the general direction of travel.
25. The method of fine-grading a pavement area which consists in maintaining earth cutting means in substantially the plane of the ultimate fine-grade, effecting continuous travel of said means while thus maintained in a general direction longitudinal to said area, and imparting thereto during said travel, a reciprocatory movement lateral of the general direction of travel.
26. A fine grading machine including a carriage adapted to be caused to travel in a plane substantially parallel with that of the ultimate fine grade over the area to be fine graded, and a shovel element mounted on said carriage for movement therewith and for movement relative to said carriage laterally of the plane of travel of the latter during such travel while the shovel edge is maintained substantially continuously in the ultimate fine-grade plane.
27. A fine grading machine including a carriage adapted to be caused to travel in a plane substantially parallel with that of the ultimate fine-grade over the area to be fine-graded, and a shovel element mounted on said carriage for movement therewith and for movement relative to said carriage lateral of the plane of travel of the latter during such travel while the shovel edge is maintained substantially continuously in the ultimate fine grade plane, and means operatively associated with said carriage and shovel for limiting said movement of said shovel relative to the carriage.
28. A fine grading machine including a carriage adapted to be caused to travel in a plane substantially parallel with that of the ultimate fine-grade over the area to be fine-graded, and a shovel element mounted on said carriage for movement therewith and for movement relative to said carriage lateral to the plane of travel of the latter during such travel while the shovel edge is maintained substantially continuously in the ultimate fine grade plane and means operatively and adjustably associated with said carriage and shovel for limiting said movement of said shovel relative to the carriage.

In testimony whereof, I have hereunto set my hand, this 17th day of November, 1924.

ROBERT D. BAKER.
